E. D. ANGELL

GOLF GAME

Filed August 19, 1925

INVENTOR

Emmett D. Angell

BY
Philip S. McLean

ATTORNEY

UNITED STATES PATENT OFFICE.

EMMETT D. ANGELL, OF CALIFON, NEW JERSEY.

GOLF GAME.

Application filed August 18, 1925. Serial No. 51,247.

To all whom it may concern:

Be it known that I, EMMETT D. ANGELL, a citizen of the United States, and a resident of Califon, county of Hunterdon, and

5 State of New Jersey, have invented certain new and useful Improvements in Golf Games, of which the following is a specification.

10 The objects of this invention are to provide a game in which the conditions and plays ordinarily encountered in the game of golf will be simulated to a large extent, providing the incentive of "practice" for the real game but involving the element of 15 competition so as to be free of the monotony of practice work and to make the game in a form readily adaptable to indoor use or for such use as on shipboard and in recreational centers.

20 In a preferred embodiment of the invention, the game is played on a mat or the like having a surface resembling the texture of the ordinary putting green, using regulation golf balls and putters and the "green"

25 thus provided is equipped at one end with say nine or eighteen "tees" from which the balls are putted successively between barriers or "hazards" to a "cup" near the opposite end of the green.

30 Other novel features of the invention will appear as the specification proceeds.

The drawing accompanying and forming part of this specification illustrates the invention as embodied in one of its most practical forms, but it should be understood that the structure may be modified from this showing without departure from the broad spirit and scope of the invention.

35 The figure in the drawing is a perspective view illustrating the complete game and the method of playing the same.

The surface of the green is provided in the present disclosure by a mat or carpet 1 having a texture approximating that of a grass green. This mat is shown supported on a wooden platform made of three sections 2, 3, 4, suitably joined in readily foldable or detachable relation.

40 This "artificial or "indoor" green is constructed in a suitable size, strong enough and with wearing qualities to support the players so that all the conditions of the real game are quite closely simulated.

45 Across one end of this "green" are arranged a series of starting points or stations which may be considered as artificial

tees 5, nine being shown in the present disclosures, numbered as 1 to 9. The number of these tees may be more or less, according to the size of the game.

50 At the opposite end of the green, a cup 6 is located which may be about the size of the usual "hole" and interposed at an intermediate point between the tees and cup, preferably somewhat nearer the cup, are 55 the obstacles or "hazards" 7, 8, spaced apart sufficiently to provide a passage 9 wider than the diameter of the golf ball 10. These hazards may be in the form of discs of wood, rubber or other material, held in position by their weight or attached fixedly to the mat or the supporting platform and their shape may vary. Thus, they may be of various angular conformations, elliptical, egg shaped or in the nature of small mounds, 60 etc., their purpose being to provide a restricted way to the cup, preventing direct access thereto from the different tees, except possibly from one or more of the centrally located tees.

65 The game is played using regulation golf balls 10 and standard putters 11. The tees are placed far enough inward from the side and end edges of the green to enable the players to take a proper stance and similarly the cup is located far enough in from the edges so that any reasonable shot will not overrun the green. The arrangement of the 70 tees provides a variety of angles which the player must shoot to approach or reach the cup and the hazards form a gateway requiring great accuracy to reach the cup in the fewest possible number of strokes. The shots are made in succession from the several tees so each new tee presents a new 75 problem with fresh possibilities, particularly because of the hazards which guard the way to the cup.

80 The usual rules as to succession in play may be observed, as in the regulation game, 100 all players completing one hole before starting the next, or special rules may be devised to add further interest. This element of interest, the factor of competition and the various "chance" possibilities provide 105 a "sporty" game, requiring the full skill of the players and giving them helpful practice without boresome routine of the usual practice work.

85 The surface of the green may be made 110 undulating, if desired, by placing suitable shaping implements under the mat. The

- cup may be formed simply as a hole in the nap of the carpet or as an opening through the carpet or a recess in the platform. In practice I have employed a canvas bag 12, 5 suspended from the under side of the platform in line with corresponding openings 13, 14, through the mat and platform. The mat or green surface may be detachably secured on the platform or may be 10 simply laid on the platform and if desired, may be used without any platform, being then laid directly on the floor. The mat is of such a structure preferably that it may be rolled and unrolled like a carpet and 15 hence be readily taken up and put down. The tees may be placed in different relations to further vary the angles and the possibilities of the game. If desired; a back stop around the edges of that green may be provided at the back of the hole. 20
- What is claimed is:
1. A golf game comprising an artificial indoor putting "green" capable of supporting the players, having a surface approximating the surface of a real golf green, a "hole" adjacent one end of said "green", successively designated "tees" at the opposite end of said green and "hazards" on said green interposed intermediate the tees and 25 hole spaced to provide a clear way between them for a golf ball and requiring the putting of golf balls from the several tees in a variety of different angular relations to pass through said way and into the hole in the fewest possible number of strokes. 30
  2. A golf game comprising a mat adapted to support the players, of a texture approximating the surface of a real golf green, said mat being of elongated outline, adapted to 35 be rolled and unrolled like a carpet and provided with a recess in simulation of a
- hole adjacent one end thereof, successively designated tee stations arranged across the opposite end portion of the mat and two obstructions on the mat intermediate the tee stations and hole spaced apart sufficiently to enable the passage of a golf ball putted from the tees toward the hole but close enough to prevent direct passage of the golf ball from all the tee stations to the hole and thereby presenting different problems in putting from the successive tees past the hazards into the hole. 45
3. A golf game comprising a substantially rectangular raised platform having a playing surface approximating the texture of a golf green and capable of supporting the players thereon, a "hole" adjacent one end of said "green", differently placed "tees" adjacent the opposite end of said green and 50 hazards on the green between said tees and hole for requiring the players to putt a golf ball at a variety of angles from the different tees to reach the hole past the hazards. 55
  4. A golf game comprising a platform, a mat on said platform having a texture approximating that of a putting green, said mat and platform having alining openings therethrough, a cup of flexible material suspended from the under side of said platform in line with the openings therethrough to form a "hole", variously placed tees on said mat at a distance from the hole and hazards on the mat between said tees and hole for 60 requiring the putting of the balls at various angles from the several tees to reach the hole past said hazards. 70

In witness whereof, I have hereunto set my hand this 14th day of August, 1925.

EMMETT D. ANGELL.
